DIVIDER FOR CHEESE MOLDS

Marvin F. Pullen, Portland, Oreg.

Application October 23, 1951, Serial No. 252,591

3 Claims. (Cl. 100—225)

1

This invention relates to a cheese mold and, more particularly, to a new and novel divider insert for use therewith.

Cheese bricks of moderate sizes, for example, two pound bricks, are molded several at a time in compartmented containers. These containers comprise a rectangular open top box having a removable divider insert consisting of a generally flat base portion adapted to rest on the bottom of the box and on which are secured, as by welding thereto, upstanding divider plates which extend transversely of the box and with the walls of the box form the compartments in which the bricks are molded. In handling the inserts during cleansing and mold assembly operations the joints between the divider plates and the base portion are often severely stressed, and in the divider inserts used in the past were frequently broken, requiring the insert to be discarded. It is an object of this invention, then, to provide a divider insert for a cheese mold wherein breakage of the divider plates from the base portion is substantially eliminated.

The divider inserts of the prior art were also difficult to remove from the mold box. Therefore, it is a further object of this invention to provide a divider insert that may be easily removed from a cheese mold box.

It is still a further object of this invention to provide a divider insert that may be easily and cheaply manufactured.

The foregoing and other objects and advantages of the present invention will be more readily ascertained from an inspection of the following specifications taken in connection with the accompanying drawing wherein like numerals refer to like parts throughout, while the features of novelty will be more distinctly pointed out in the appended claims.

According to the embodiment herein shown, there is provided in the present invention a divider insert including a substantially flat base portion having a plurality of parallel, transversely extending channels formed in the upper surface of the base, as by stamping, with a corresponding series of ribs projecting from the lower surface of the base. Welded in each of the channels is a normally projecting flange of an upstanding divider plate extending transversely of the base whereby a strong joint is formed between the base portion and a divider plate that is not easily broken. The ribs have a functional operation resulting in the easier removal of the insert from the mold box. For a more detailed description of the invention, reference is made to the accompanying drawing, wherein:

Fig. 1 is a perspective view of a cheese mold with a side and an end of the mold box broken away to show the divider insert of this invention;

Fig. 2 is a side elevation taken along line 2—2 of Fig. 1 showing a mold filled with cheese and

2

with a pressure foot in position in the mold; and

Fig. 3 is an enlarged cross-sectional view of the joint between a divider plate and the base portion of the insert formed in accordance with the present invention.

Referring now to Fig. 1, there is shown therein a cheese mold box 10 having a bottom 11 and opposite side walls 12 and end walls 13. Preferably the walls taper slightly outwardly from the bottom of the box to facilitate removal of the molded cheese. To increase the strength of the box the tops of the end and side walls are rolled over as at 14 with an additional brace 15 welded to each of the top corners. Additional strengthening of the box is also afforded by the channels 16 welded to the side walls 12 and extending the length of the box. The bottom of the box is preferably perforated at intervals by small holes 17 to permit drainage of the whey when cheese is compressed in the mold.

Dividing the box 10 into compartments of approximately equal volume is a removable divider insert 20 having a base portion 22 with a plurality of transversely extending divider plates 21 secured to the upper surface thereof. The improved manner of constructing the divider inserts 20 in accordance with my invention includes offsetting as by stamping, narrow, transversely extending, parallel strips of the base portion 22 so as to form channels 23 in the upper surface of the base portion and corresponding ribs 24 on the lower surface thereof. Preferably the strips are offset to form channels of a depth equal to the thickness of the divider plates 21, which may be made of about a 14-gauge steel plate, as may be the base portion 22; it being understood, of course, that other weights of sheet and other materials may be used. The divider plates 21 are formed with a normally projecting flange 30 on their lower edge of a width whereby the flange will comfortably fit within the channels 23, as best shown in Fig. 3. Preferably the edge of a flange is tapered as indicated at 31 so that it conforms closely to the contour of the sides of the channel. The divider plates 21 may be permanently affixed to the base portion 22 by spot-welding the abutting surfaces of the flange 30 and channel 23 at intervals, as indicated at 32; other methods of securing the plate 21 to the base portion 22 will be apparent. To support the base portion 22 evenly on the bottom of the box the opposite ends are folded under for a short distance as shown at 35, thereby forming ribs corresponding in height to ribs 24. Drainage of whey from the mold is facilitated by the provision of holes 36 in base portion 22.

The assembled insert is preferably provided with a protective coating 33, such as by dipping or spraying with tin. After this tinning operation any cracks and crevices remaining should be filled with solder, such as at 34, so as to obtain a smooth, easily cleaned surface. Tapering the

flange at its end 31 results in such a narrow crevice between the edge of the flange and the side of the channel that the tinning operation generally serves to fill the crevice and the soldering treatment of that joint is not necessary.

In molding bricks of cheese the mold box 10 with the divider insert 20 in place is filled with cheese curd 40. A pressure foot 41 having plates 42 adapted to just fit within the compartments is then placed on the mold and pressure is applied to the bottom of the box 10 and to pressure foot 41 so as to force the plates 42 into the compartments. This pressing compacts the curds 40, squeezing out any whey which drains from the mold through holes 36 in base plate 21 15 and holes 17 in the bottom 11 of box 10.

After the curds have been sufficiently compacted, the pressure foot 41 is removed from the mold and the mold box inverted to allow the cheese bricks formed by the compacting to drop out of the mold. An advantage of the present invention is realized at this point, for almost invariably the divider insert 20 made in accordance with my invention will drop freely from the mold when it is inverted. This was not true of the inserts of the prior art in which the base plates were formed with a substantially continuous planar surface that closely contacted the bottom 11 of the cheese mold box 10. In compressing the bricks, some of the curd is inevitably forced through the drainage holes of the base plate and spreads between the base plate and the bottom of the box. In the case of the prior art inserts wherein the base portion of the insert and the bottom of the cheese mold box were in close contact, a thin spread of cheese was frequently formed between the surfaces, creating in effect a glue line that was hard to break and often made it difficult to remove the insert because of the suction areas created thereby. Though perforations were provided in the bottom of the box and in the base plate, they too frequently plugged up with cheese to be of material assistance in admitting air to break the suction. In the divider insert of the present invention, however, this difficulty does not occur, since the ribs 24 and 25 which contact the bottom 11 of the mold box support the major areas of the base portion 22 at a distance from the bottom of the mold box sufficient to prevent the formation of suction areas and consequently the inserts of the present invention may be easily removed from the mold box.

Breakage of divider plates from the base has been substantially eliminated in cheese molding operations utilizing the inserts of the present invention. This is because the major portion of the stress developed by strain between the divider plates and the base is taken up by the bend at the flange so that relatively little stress is applied to the welds securing the divider plate to the base portion.

It can be seen, therefore, that, in accordance with the present invention, divider inserts can be easily and economically fabricated to attain a structure that by its nature has distinct advantages over the divider inserts of the prior art.

Having illustrated and described a preferred embodiment of the invention, it should be apparent to those skilled in the art that the invention permits of modification in arrangement and detail. I claim as my invention all such modifications as come within the true spirit and scope of the appended claims.

I claim:

1. In a rectangular cheese mold, having a bottom wall and opposite side walls: a divider insert including a substantially flat base portion having upper and lower surfaces, and a plurality of flat divider plates secured to said upper surface of said base portion and upstanding therefrom, said base portion being rectangular and adapted to closely fit within said mold, and formed with a plurality of narrow, longitudinally spaced-apart, transversely extending, offset portions defining channels in said upper surface of a depth equal to the thickness of said plates, said offset portions defining ribs projecting from said lower surface whereby when said insert is placed in said mold said ribs will contact the bottom of said mold with the portions of said base portion between said ribs spaced a distance from said bottom, said divider plates including a normally extending flange portion on the bottom edge thereof fitting cooperatively within said channels, the edge of said flanges being tapered to substantially conform to the contour of the sides of a channel, said plates being secured to said base with the flange portion of a plate inserted in a channel, and means rigidly securing said flange portions to said plate.

2. In a rectangular cheese mold, having a bottom wall and opposite side and end walls; a divider insert including a substantially flat, rectangular base portion having an upper and a lower surface, said base portion having a plurality of longitudinally spaced apart, transversely extending offset portions defining channels in the upper surface of said base portion and ribs depending from said lower surface, a plurality of upstanding, spaced-apart divider plates, each having a normally extending flange formed at the lower end thereof of a width equal to the width of said channel, said plates being secured to said base portion with the flanges of one of said plates inserted in a corresponding one of said channels, means rigidly securing said flanges to said base portion, and a protective coating of tin over the entire insert assembly.

3. A divider insert for a cheese mold of the class described, said insert including a substantially flat base portion having upper and lower surfaces and a plurality of flat, upstanding, divider plates secured to said upper surface of said base portion, said base portion being adapted to fit closely within said mold and having a plurality of parallel, transversely extending narrow strips offset the thickness of said plates whereby channels are formed in the upper surface of said base portion and ribs are formed on the lower surface of said base portion, each of said divider plates having an end portion extending at right angles to the general plane of the plate, said end portion being of a width equal to the width of said channel, said plates being secured to said base with said end portion of one of said plates inserted in a corresponding one of said channels, and means securing said plate end portions to said base portion.
